O. G. CRITCHETT.

Improvement in Eyeleting Machines.

No. 122,366.

Patented Jan. 2, 1872.

UNITED STATES PATENT OFFICE.

OLIVER G. CRITCHETT, OF STONEHAM, ASSIGNOR TO HENRY ELMER TOWNSEND, OF BOSTON, MASSACHUSETTS.

IMPROVEMENT IN EYELETING-MACHINES.

Specification forming part of Letters Patent No. 122,366, dated January 2, 1872.

To all whom it may concern:

Be it known that I, OLIVER G. CRITCHETT, of Stoneham, in the county of Middlesex and State of Massachusetts, have invented certain Improvements in Eyeletting-Machines; and I do hereby declare that the following, taken in connection with the drawing which accompanies and forms part of this specification, is a description of my invention sufficient to enable those skilled in the art to practice it.

My invention relates to the organization and method of driving the mechanism of an eyeletting-machine.

In common eyeletting-machines, or those of the more approved kinds, there are the following instrumentalities: A rotating eyelet-box or hopper; a vertically-reciprocating eyelet-pin and set that receive the eyelet and set it against a stationary set; and an inclined reciprocating chute.

These machines are usually worked by the reciprocations of a lever and pedal mechanism; and the process of setting eyelets by them is slow, tedious, and not thoroughly effective; and the primary object of my invention has been to so connect the parts with a rotary shaft that the intermittent rotative movement of the hopper, the reciprocating movement of the hopper and chute, and the vertically-reciprocating movement of the setting-tool may all be effected by the continuous and unintermittent movement of said shaft; and my invention consists primarily in combining the horizontally-reciprocating chute, the rotating hopper, and the vertically-reciprocating setting device with a shaft in such manner that the rotative movement of the shaft effects all of the movements of the machine. The invention further consists in so combining and arranging the mechanism that the chute first goes forward and brings the eyelet at its lower end directly over the receiving-pin; the chute then stops and the pin ascends, passing into and through the stationary eyelet; the chute next draws back, leaving the eyelet on the pin, and the pin next rises with the eyelet, and while so rising the chute is stationary, the chute being stationary during the setting operation, and the setting mechanism being stationary when the chute goes forward, and when it draws back after the eyelet is received upon the pin.

The drawing represents a machine embodying the improvements, A and B being, respectively, opposite side elevations, and C being a front view.

a denotes a stationary frame; *b*, a horizontal shelf upon the same, upon which shelf is supported and slides the bottom plate *c* of a triangular frame piece, *d*, having on its inclined top the chute or roadway *e*, made in the usual way, and provided with the usual eyelet-box or hopper, which holds the eyelets, and by its rotative movement keeps the chute sufficiently filled with eyelets. The chute-plate or frame slides horizontally upon the top of the frame *a*, and is guided and kept in place by a stationary pin, *f*, which extends through a slot, *g*. At the rear end of the chute-board or frame is a tail piece, *h*, from which extends a pin, *i*, into a cam-slot, *k*, in one side of a cam-wheel, *l*, fixed on a rotary cam and driving-shaft, *m*. *n* denotes the vertical shaft, on top of which is formed the movable eyelet-set *o*, which acts in conjunction with the stationary set *p* to clinch or set the eyelet when the shaft is raised. In the shaft *n* is the spring-pin *q*, which passes through or impales the eyelet at the end of the chute, the pin yielding against the stationary pin *r* when the set *o* rises. The shaft *n* is jointed by a link, *s*, with one arm, *t*, of a bent rocker-lever, fulcrumed at *u*, whose other arm has a pin, *v*, projecting into a cam-groove, *w*, in the cam-wheel *l* on the shaft *m*. Another arm, *x*, extends from the lever, and is connected by a link, *y*, with an arm projecting from the shaft or pin on which the eyelet-box *z* is mounted. As the shaft *m* is rotated the cam *k* actuates the chute, and the cam *w* actuates the movable eyelet-set and the eyelet-box or hopper, the operations being continuous and requiring no cessation, as in pedal-operated machines, the operations of the machine being more uniform and certain than by the spasmodic operations of the old machines. The formation of the cams *k* and *w* are such that, when the set *o* is down to its lowest position and at rest, the chute is thrown forward and brought to a stop; the set *o* is then moved up, the chute being stationary, and the pin enters the lowermost eyelet of the chute; the set then stops and the chute retreats; and the chute then stops and the movable set rises, the chute being station-

ary, with its pin-impaled eyelet, and the eyelet is set. The set then descends, the chute being still stationary, and the parts are then in position for the chute again to advance for presenting another eyelet to the pin.

In operating an eyelet-machine by a pedal mechanism the movement of the lower or movable set is greater or less, in accordance with the thickness of the stock. But in the cam-operated machine the throw of the movable set is necessarily constant or positive in extent; and if the sets come together when no stock is in the machine the lower set, of course, could not reach the highest point of its throw when stock is interposed, unless provision is made for some yield in the sets. I, therefore, place over the upper set a strong spring, *j*, which yields when a stress greater than that required to set the eyelet is brought to bear against it; and as the

stock increases in thickness this spring yields, permitting the lower set to complete its throw.

I claim—

1. In combination with the horizontally-reciprocating chute and hopper, the rotative eyelet-box or hopper and the vertically-reciprocating eyelet-receiving and setting mechanism, the rotating cam-shaft and its cams, by which the chute, hopper, and eyelet-set are continuously and automatically operated, substantially as described.

2. Also, in combination with a movable set having a constant or fixed throw, an upper or anvil-set made to yield against the stress of a suitable spring, substantially as described.

O. G. CRITCHETT.
